UNITED STATES PATENT OFFICE.

PHILO O. SOPER, OF NEW YORK, ASSIGNOR OF ONE-HALF TO JAMES STEEL, JR., OF BROOKLYN, NEW YORK.

MOUTH-PIECE FOR BAGS.

SPECIFICATION forming part of Letters Patent No. 392,236, dated November 6, 1888.

Application filed July 11, 1888. Serial No. 279,626. (No model.)

To all whom it may concern:

Be it known that I, PHILO O. SOPER, of the city and State of New York, have invented a certain new and useful Mouth-Piece for Bags, 5 of which the following is a specification.

The object of my invention is to provide a mouth-piece for cloth bags—especially for small tobacco-bags, though it may be used with bags of any size and for any purpose—that 10 may be readily secured in place by means of the usual string threaded in the gathered mouth of the bag, or by any other suitable means, that is so constructed as to be retained in place by reason of its own shape, and that 15 is so designed that in opening it the encircling cord and bag-mouth are stretched but little, and yet the mouth-piece when opened presents a large throat or passage for filling or discharging the contents of the bag.

20 A further object of the invention is to so construct the mouth-piece that it projects but slightly beyond the mouth of the bag and does not materially encumber it or render it inconvenient to be carried in the pocket by a smoker, 25 and yet when thrown open a passage of ample capacity is provided for the ready discharge of the tobacco or other contents.

For convenience I provide the device with a spring which retains it in the open position, 30 but automatically closes it when a slight motion sufficient to throw the strain of the spring above the hinge or pivot is imparted to it by hand. This device is, so far as I am aware, new in construction and general operation, and 35 I do not therefore limit myself to the specific details of construction shown in the accompanying drawings.

I have here illustrated the invention embodied in one form which I consider the most 40 practical now known to me; but obviously those skilled in such matters may vary the details of structure in many respects without departing from the spirit of the invention.

Figure 1 is a side elevation of the mouth-piece closed; Fig. 2, a similar view, and Fig. 3 a plan of the mouth-piece open; Fig. 4, an elevation of the narrower side of a small bag—say, a two-ounce tobacco-bag—with the mouth-piece in place; and Fig. 5, a detail view illustrating the use of the ordinary double-ball

clasp for closing the mouth-piece when a spring is not employed.

The mouth-piece is composed of two like sections, A B, formed each with three sides, two sides—preferably the narrower ones, *a a* 55 or *b b*—being of equal width and at right angles to the third side, *a'* or *b'*, and the sides *a b* are hinged upon each other at *c*. In other words, each section in cross section preferably presents a rectangle with one of the sides removed. The hinge-connections between the sides *a* and *b* of the respective sections are located on lines drawn at right angles from the other sides, *a' b'*, at points about equidistant between their ends. The sides *a b* are cutaway on 60 an angle or bevel just below the hinges, as shown at *z*. Consequently when closed the mouth-piece, as shown in Fig. 1, presents the approximate form of an isosceles triangle, the width of the side pieces, *a b*, being such that the 65 distance from the hinge *c* to the apex and faces of the triangle are about the same. At points about midway of the lengths of the sides *a' b'*, but preferably slightly below lines perpendicular to said sides and running to the hinge, fingers or lips *d* are formed. These may serve to hold a spring, *e*, for closing the mouth-piece. The strain of the spring when the mouth-piece is forced open is somewhat below the hinge *c*, Fig. 2, and consequently it also serves to hold 70 the mouth-piece open. If the spring were located higher up it would always tend to close the sections. Stops *f*, formed on the sides *a* or *b* of one of the sections, serve to limit the opening of the mouth-piece to such a point 75 that when open the sides *a' b'* still incline from the bottom inwardly, as shown in Fig. 2.

The mouth-piece thus constructed—preferably of sheet metal—may be made of any desired size and used for any purpose. It is 80 preferably secured in place by tying the mouth of the bag under the fingers *d*, which are provided specially for that purpose.

The pyramidal shape of the mouth-piece, whether closed or open, tends to prevent its 85 withdrawal from the bag.

Since the edge of the bag-mouth is in a line but slightly above the hinge *c*, those portions of the mouth-piece supporting the bag move in opening through but a short vertical arc, 90

and consequently the mouth of the bag is stretched but little. There is always sufficient elasticity in the cord to permit this movement, and the expansion is so slight as not to impair 5 or materially loosen the connection between the bag and mouth-piece.

The construction above described is such that while the motion at the edge or mouth of the bag is small the throat of the mouth-piece 10 presents a large opening, as may readily be observed from the drawings.

As shown in Fig. 5, I might dispense with the spring and employ the ordinary double-ball clasp α . I prefer, however, to use a spring 15 and to use it in the manner shown, so that the mouth-piece will stand open, as in Fig. 2.

The parts of this device may be struck out of sheet metal at a very small expense. The mouth-piece may be sold separately or may be 20 furnished by dealers with bag-packages of tobacco, &c. When attached to an ordinary bag of tobacco it will preferably be applied, as in Fig. 4, so as to open at right angles to the greater width of the bag.

25 I claim as my invention—

1. A mouth-piece formed of like sections $a a'$ and $b b'$, hinged together and having the sides $a b$ beveled at z , as shown and described.

2. A bag mouth-piece formed of like sections 30 $a a'$ and $b b'$, hinged upon each other at c , and having a stop, f , the hinges being located in lines drawn at right angles to the sides $a' b'$, from points equidistant between their ends, and the sides $a b$ being beveled at z , substantially as shown and described.

35 3. The combination, with the spring, of the

like sections $a a' a'$ and $b b' b'$, hinged upon each other, beveled at z , and having a stop, f , substantially as set forth.

4. The combination of the like sections $a a'$ 40 and $b b'$, hinged together at c by their sides $a b$, and having the lips or fingers d , substantially as set forth.

5. The combination of the sections having sides $a b$ at right angles to the sides $a' b'$, and 45 hinged or pivoted together at c , the distances from the hinge to each side a' or b' , measured on a line at right angles to said sides, being approximately equal to the distance from the hinge to the upper edges of said sides. 50

6. The sections having each three sides, $a a'$ or $b b'$, and $a' b'$, the sides $a b$ being hinged upon each other at c , and beveled at z , as shown, and the distance from the hinge to the sides $a' b'$, measured on a line at right angles to said 55 sides, being approximately equal to the distance from the hinge to the edges of said sides, in combination with bag-retaining fingers or devices located at about midway of the length of the sides $a' b'$. 60

7. The combination, with a bag, of a mouth-piece formed of like sections hinged upon each other, and of general triangular shape having its larger end within the bag, and the bag secured thereto on a line slightly above the hinge, 65 substantially as set forth.

In testimony whereof I have hereunto subscribed my name.

PHILO O. SOPER.
